OVERLOAD RELAY

Leo J. Berberich, Pittsburgh, Pa., assignor to
Westinghouse Electric Corporation, East Pitts-
burgh, Pa., a corporation of Pennsylvania

Application July 31, 1947, Serial No. 765,114

6 Claims. (Cl. 200—122)

1

This invention relates, generally, to overload relays, and, more particularly, to temperature sensitive overload relays having a liquid electrode which may be utilized as a switching member.

In the design of low-cost relays, many attempts have been made to utilize the equivalent of a mercury switch for making and breaking energized circuit connections. One of the greatest obstacles to overcome in producing such a relay has been the contamination of the mercury due to arcing caused by the interruption of circuits and the resultant change in the characteristics of the switch. This renders it impossible to calibrate the relay properly and to make it function within predetermined limitations. Therefore, such a relay does not give adequate protection to electrical apparatus.

The object of the invention is to provide for maintaining the vapor-pressure characteristics in a mercury switch substantially constant, and to protect the mercury from contamination.

For a fuller understanding of the nature and objects of the invention, reference may be had to the following detailed description, taken in conjunction with the accompanying drawing, in which the single figure is a view in vertical section of a relay constructed in accordance with this invention, in conjunction with a diagram showing how it may be connected in a circuit.

Referring now to the drawing, the relay shown generally at 10 comprises a metallic bellows-like member 11 having a bottom plate or member 12 and a top plate or member 13 sealed thereto, making a container for a purpose to be described hereinafter.

The bellows-like member 11 may be made of any suitable material. In making a relay for test purposes, the bellows-like member 11 was made from stainless steel and was mounted on a stainless steel plate 12. The member 11 may be sealed to the plate 12 in any suitable manner well-known in the art. In the embodiment illustrated, it is welded.

The characteristics of the stainless steel bellows member 11 will affect the operation of the relay. Therefore, before building a relay, it is necessary to have detailed information on the stiffness of the bellows member. However, this can readily be established by any one skilled in the art, and a table may be prepared giving the

2

resistance of such members to expansion or contraction.

The top plate 13 may also be made of stainless steel. After certain materials have been placed in the container, the plate 13 may be welded to the bellows-like stainless steel tube 11. As shown, the plate 13 has an electrode 14 depending therefrom. This electrode 14 is insulated from the stainless steel plate 13, as shown at 15. Any suitable type of insulating material may be employed. In this modification of the invention, an elastomeric organosilicon oxide, such as dimethyl silicone rubber-like compositions, is employed to give a tight seal as well as to insulate the electrode 14.

Before the plate 13 is welded to the bellows-like member 11, a quantity of mercury 16 is poured into the bottom of the container. The amount of mercury employed will depend upon conditions to be met. In this instance, the amount of mercury must be great enough for the end of the electrode 14 to be sufficiently immersed to make good electrical contact.

In order to protect the mercury from contamination during the operation of the relay, a layer of liquid fluorocarbon 17 is provided. Since the specific gravity of liquid fluorocarbons is much less than that of mercury, it floats as illustrated. The amount of fluorocarbon floated on the mercury will be selected to meet the conditions to which the relay will be subjected.

In operating a relay having a layer of fluorocarbon floating on the mercury, it was discovered that the fluorocarbon did not readily decompose when subjected to arcing, and when it did decompose, it did not produce materials which contaminated the mercury.

It has been found that completely fluorinated cyclic hydrocarbons with or without completely fluorinated side chains, and the completely fluorinated straight chain or aliphatic fluorocarbons may be utilized singly or in admixtures with one another with success for protecting mercury from contamination.

Examples of the completely fluorinated cyclic hydrocarbons are such as perfluoro-methyl-cyclohexane, C_7F_{14} , perfluoro 1,3-dimethyl-cyclohexane, C_8F_{16} , perfluoro 1,3,5-trimethyl-cyclohexane, C_9F_{18} . Examples of completely fluorinated straight chain or aliphatic hydrocarbon liquids

that may be used are perfluoro-heptane, C_7F_{16} and perfluoro-octane, C_8F_{18} .

The structure of these completely fluorinated cyclic hydrocarbons is as follows:

The structure of the completely fluorinated straight chain hydrocarbons which may be utilized is given below:

It has been found that these liquid fluorocarbons are very stable with the result that the relay retains substantially constant vapor-pressure characteristics. In other words, when the relay having fluorocarbon liquids floating on the mercury is operated a number of times, it continues to give substantially the same curve of vapor pressures with change in temperature. Therefore, when the stiffness characteristics of the bellows-like member 11 are known and the fluorocarbon is properly selected, the relay may readily be calibrated and it will not change appreciably during operation. Therefore, relays may be built to perform any predetermined operation.

In order to make the relay respond to predetermined overload conditions, a heating coil 18 is disposed around the member 11. This heating coil will be connected in some predetermined circuit relation with the apparatus to be protected. In this instance, a shunt motor shown generally at 19 is connected in series-circuit relation with the coil 18. As the motor 19 is overloaded, the current flowing in the heating coil 18 will gradually raise the temperature, increasing the vapor pressure in the container causing it to expand and withdrawing the electrode 14 from the mercury. In order to explain the complete functioning of the relay 10, a brief description of its functioning in connection with the motor will be given.

Assuming now that the manually-operated switch 20 and the push-button switch 21 are both closed, then a circuit is established which extends from one conductor of the power line 22 through conductor 23, switch 20, the mercury 16, functioning as one of the members of the switch of the relay 10, the electrode 14, which is the other member of the switch, conductor 24, the actuating coil 25 of the relay 26, conductor 27, push-button switch 21 and conductor 28, back to the other conductor of the power line 22.

The relay 26 will be actuated upwardly and the contactor 29 will bridge its contacts and establish a holding circuit through conductor 30

which parallels the push button 21. In this manner, the relay 26 is held in its raised position after the push-button switch is released.

Upon the operation of relay 26, an actuating circuit for the relay 31 is established which extends from one conductor of the power line 22 through conductors 23 and 32, the actuating coil 33 of the relay 31, conductor 34, contact member 35 of the relay 26, conductor 36, back to the power line 22.

Upon the operation of relay 31, a motor circuit is established from the power line through conductor 38, contactor 39 of the relay 31, conductor 40, motor 19, conductor 41, the heating coil 18 of the relay 10, conductor 42, contact member 43 of the relay 31 and conductor 44, back to the power line.

Assuming now that the motor 19 becomes overloaded, the current in the motor circuit will be increased thus causing an increase of current flow through the heating coil 18. This results in raising the temperature of the liquid fluorocarbon in the container comprising the members 11, 12 and 13. The liquid fluorocarbon will boil increasing the vapor pressure and expanding the bellows member 11. Upon a predetermined expansion of the bellows member 11, the electrode 14 will be withdrawn from the mercury 16 interrupting the holding circuits of the relay 26 with the result that relay 31 also is opened, interrupting the motor circuit.

As the relay cools down, the bellows member 11 will contract and the electrode 14 will again be dipped into the mercury 16. The motor stands idle until the motor circuit is again closed by operating the push button 21.

Test results have shown that when a layer of, for example, perfluoro 1,3-dimethyl-cyclohexane or perfluoro-heptane was floated on the mercury 16, and the relay operated five hundred times by a control voltage of 440 volts with the switch members 14 and 16 interrupting a current flow of one-tenth of an ampere, no contamination of the mercury resulted. The vapor-pressure characteristics of the relay did not change.

It is pointed out that the boiling point of perfluoro 1,3-dimethyl-cyclohexane is 101° C. at 760 mm. mercury, while the boiling point of perfluoro-heptane is 82° C. at 760 mm. mercury. Therefore, in designing the relay, in order to get a predetermined operation, it becomes necessary to take these boiling temperatures into account, using either fluorocarbon alone or mixtures thereof.

In some instances, after long operation of the relay with a layer of these liquid fluorocarbons floating on the mercury, small quantities of unsaturated aliphatic fluorocarbons, such as C_2F_4 and C_3F_6 were produced. These products do not contaminate mercury. Further, since only small quantities of C_2F_4 and C_3F_6 are produced, the vapor-pressure characteristics of the relay remain substantially constant with temperature and the relay continues to operate in response to substantially the same predetermined load conditions on the motor.

It has been found in operating with relays having a layer of non-fluorinated hydrocarbon liquids floating on the mercury that the arcing caused by the separation of the switch members 14 and 16, readily decomposed the hydrocarbons and caused a considerable amount of fouling of the mercury. The result of the breaking down of the hydrocarbon is that the relay begins to operate at lower and lower temperatures. Therefore,

relays containing non-fluorinated hydrocarbons will not function an appreciable number of times in accordance with the calibrations.

Since numerous changes may be made in the above-described structures and different embodiments of the invention may be made without departing from the spirit and scope thereof, it is intended that all matter contained in the above description or shown in the accompanying drawing shall be interpreted as illustrative and not in a limiting sense.

I claim as my invention:

1. In a switch, in combination, a container capable of expanding and contracting in response to changes in internal pressure, mercury in the container to be used as one of the electrodes of the switch, a second electrode disposed in the container to move into and out of the mercury as the container contracts and expands, respectively, with changes in internal pressure to perform switching operations, and a quantity of a completely fluorinated hydrocarbon liquid floating on the mercury to maintain substantially constant vapor-pressure characteristics in the container and to protect the mercury from contamination during the operation of the switch to make and break circuits carrying electric current.

2. In a switching device, in combination, a container capable of expanding and contracting in response to changes in internal pressure, mercury in the container, the mercury serving as one electrode of the switch, a second electrode disposed in but insulated from the container to move into and out of contact with the mercury as the container contracts and expands in response to changes in internal pressure, and a quantity of liquid perfluoro 1,3-dimethyl-cyclohexane floating on the mercury to maintain substantially constant vapor-pressure characteristics in the container and to protect the mercury from contamination during the operation of the switching device to make and break circuits carrying electric current.

3. In a switching device, in combination, a metallic bellows-like container capable of expanding and contracting in response to changes in internal pressure, mercury in the container, the mercury being disposed to function as one electrode of the switching device, a second electrode disposed in the container and insulated from it, the second electrode moving with the container as it expands and contracts with changes in internal pressure to break and make contact with the mercury, a quantity of perfluoro-heptane floating on the mercury to maintain substantially constant vapor-pressure characteristics in the container and to protect the mercury from contamination during operation of the switching device to make and break circuits in which electric current is flowing.

4. In a relay provided with a switching device, in combination, a metallic bellows container hav-

ing predetermined resistance to expansion by internal pressure, mercury in the container constituting one electrode of the switching device, a second electrode disposed in the top of the container and insulated therefrom to move with the container as it expands and contracts to break and make contact with the mercury, a quantity of fluorocarbon floating on the mercury, the fluorocarbon comprising a mixture of perfluoro 1,3-dimethyl-cyclohexane and perfluoro-heptane the fluorocarbon floating on the mercury serving to maintain substantially constant vapor-pressure characteristics in the container and to protect the mercury from contamination during operation of the switch to make and break circuits in which electric current is flowing.

5. In a relay provided with switching members, in combination, a metallic bellows container having a predetermined resistance to expansion by internal pressure but responsive to internal pressures, mercury in the container, the mercury serving as one of the switching members of the relay, a second electrode disposed in and insulated from the container to move into and out of contact with the mercury as the bellows container contracts and expands in response to internal pressure, and a quantity of a liquid fluorocarbon consisting of at least one selected from the group consisting of perfluoro 1,3-dimethyl-cyclohexane, perfluoro-heptane, perfluoro - methyl - cyclohexane, perfluoro 1,3,5-trimethyl-cyclohexane and perfluoro-octane floating on the mercury, the liquid fluorocarbon serving to maintain substantially constant vapor-pressure characteristics in the container and to protect the mercury from contamination during operation of the switch members to make and break circuits carrying electric current.

6. In a relay provided with a plurality of switch members, in combination, a bellows container having a predetermined resistance to expansion in response to internal pressure, mercury in the container constituting one of the switch members, an electrode disposed in the container and insulated therefrom constituting the other switch member, the electrode being disposed to move as the container expands and contracts to break and make contact with the mercury, a quantity of liquid fluorocarbon floating on the mercury to maintain substantially constant vapor-pressure characteristics in the container and to protect the mercury from contamination during operation of the switch members to make and break circuits carrying electric current, and a heater disposed around the container, the heater serving to regulate the temperature of the container, the mercury and fluorocarbon in accordance with the operating conditions.
